Primary Examiner — Susan E Krakower*Assistant Examiner* — Andrew Kerr*(74) Attorney, Agent, or Firm* — Soroker Agmon Nordman(57) CLAIM

The ornamental design for a set of pins for corks decoration, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front side left-corner perspective view of a set of pins for corks decoration showing our new design;

FIG. 2 is a back side left-corner perspective view thereof;

FIG. 3 is a side right-corner perspective view thereof; and,

FIG. 4 is a front side right-corner perspective view thereof. The broken line showing the box is included for the purpose of illustrating environment that forms no part of the claimed design.
